AMPLIFIER CIRCUIT

Henri Petrus Johan Verbeek, Voorburg, and
Bernardus Dominicus Hubertus Tellegen, Eindhoven, Netherlands, assignors, by mesne assignments, to Radio Corporation of America, New York, N. Y., a corporation of Delaware

Application October 28, 1936, Serial No. 107,920
In Germany November 11, 1935

2 Claims. (Cl. 179—171)

This invention has reference to a circuit arrangement for amplifying electric oscillations which transmits a particularly large range of frequencies, for example, from 20 to 2×10^6 cycles. Such amplifier arrangements are used inter alia for television purposes.

It is well-known that in the usual aperiodic amplifiers (resistance amplifiers) amplification decreases in the case of comparatively high frequencies due to the unavoidable parasitical capacity between the anode and the cathode of the amplifier valves and between the conductors connected to said electrodes. In order to increase amplification for comparatively high frequencies, it has been proposed before that the anode circuit of the amplifier valves should include in series an inductance and a resistance. Thus, as a matter of fact, a flatter curve of the frequency characteristic is obtained.

According to the invention, a further improvement is ensured in an amplifier circuit arrangement in which the anode circuit of one or more amplifier valves includes an impedance formed by the series combination of an inductance and a resistance by connecting in parallel with part of this impedance a capacity or the series combination of an inductance and a capacity.

In order that the invention may be clearly understood and readily carried into effect, it will now be described more fully hereinafter with reference to the accompanying drawing, in which:

Figs. 1 and 2 show familiar amplifier circuits; Figs. 3, 4 and 5 show three examples of circuit arrangements embodying the invention.

Fig. 1 shows a customary resistance amplifier. The oscillations to be amplified are supplied to the terminals *a* and *b*, whereas the oscillations amplified are obtained from the terminals *c* and *d* which are connected to the control grid and the cathode of a second amplifier valve (not shown). In the case of particularly low frequencies of the oscillations to be amplified a decrease in amplification occurs as a result of the influence of the coupling condenser C_g and of the leak R_g . This influence is, however, negligible in the case of comparatively high frequencies. If the reaction of the anode is but small, an alternating current SV_g occurs in the anode circuit by reason of the voltage V_g supplied between the control grid and the cathode, S designating the mutual conductance of the amplifier valve. For comparatively high frequencies, the voltage between the terminals *c* and *d* is consequently: $SV_g Z_a$, Z_a being the impedance of the anode circuit. The amplification of the circuit

arrangement is consequently SZ_a . For the circuit arrangement of Fig. 1, the amplification for oscillations having an angular frequency ω is:

$$V_\omega = \frac{SR}{\sqrt{1 + \omega^2 C_a^2 R^2}} \quad 5$$

in which C_a is the parasitical capacity between the anode and cathode of the amplifier valve and between the conductors connected to the electrodes. For lower frequencies, the amplification is approximately $V_0 = SR$. Consequently:

$$\frac{V_\omega}{V_0} = \frac{1}{\sqrt{1 + \omega^2 C_a^2 R^2}} = \frac{1}{\sqrt{1 + a\omega^2}} \quad 10$$

For ensuring a frequency characteristic the curve of which is as flat as possible, the factor a should be a minimum, that is to say R should be a minimum. The flatter the curve of the frequency characteristic, the smaller is consequently the amplification.

Thus, when considering the familiar circuit arrangement of Fig. 2 in which the anode circuit includes in series an inductance L and a resistance R , the following equation may be set up for this circuit arrangement.

$$\frac{V_\omega}{V_0} = \sqrt{\frac{\frac{L^2}{R^2}}{1 + \omega^2 (C_a^2 R^2 - 2LC_a) + \omega^4 L^2 C_a^2}} = \sqrt{\frac{1 + a_1 \omega^2}{1 + a_2 \omega^2 + b_2 \omega^4}} \quad 20 \quad 30$$

The curve of the frequency characteristic of the amplifier is rendered as flat as possible by making $a_1 = a_2$ and by reducing b_2 as far as possible. It is found that in the case of equal amplification a flatter curve of the frequency characteristic is obtained than in the circuit arrangement shown in Fig. 1.

According to the invention, the circuit arrangements shown in Figs. 3 and 4 have a capacity C connected in parallel with part of the impedance of the anode circuit, which is constituted by the series combination of an inductance L and a resistance R , the capacity C being connected in the circuit arrangement shown in Fig. 3 in parallel with the resistance R , and in the circuit arrangement shown in Fig. 4 in parallel with the inductance L . As an alternative, the capacity C may be connected in parallel with part of the resistance R and/or with part of the inductance L .

In the circuit arrangements shown in Figs. 3

and 4, calculation discloses for $V\omega/V_0$ a form of the shape:

$$5 \quad \frac{V\omega}{V_0} = \sqrt{\frac{1 + a_1\omega^2 + b_1\omega^4}{1 + a_2\omega^2 + b_2\omega^4 + C_2\omega^6}}$$

The curve of the frequency characteristic is rendered as flat as possible by making $a_1=a_2$ and $b_1=b_2$ and by reducing C_2 as far as possible. If 10 the connecting elements are properly chosen, these circuit arrangements give an essential improvement in comparison with the circuit arrangement shown in Fig. 2.

A further improvement is obtained by means of 15 the circuit arrangement shown in Fig. 5 in which the series combination of a capacity C and an inductance L^1 is connected in parallel with the resistance R . In this circuit arrangement $V\omega/V$ is found to have a form of the shape:

$$20 \quad \frac{V\omega}{V_0} = \sqrt{\frac{1 + a_1\omega^2 + b_1\omega^4 + c_1\omega^6}{1 + a_2\omega^2 + b_2\omega^4 + c_2\omega^6 + d_2\omega^8}}$$

The curve of the frequency characteristic is rendered as flat as possible by making $a_1=a_2$, 25 $b_1=b_2$ and $c_1=c_2$ and by reducing d_2 as far as possible.

When in the circuit arrangements shown in 30 Figs. 3, 4 and 5, the said conditions ($a_1=a_2$, and so forth) are dropped, the frequency characteristic is possessed of a few maximum or minimum values. These maximum and minimum values may be used in certain cases for the purpose either of increasing the range of frequencies 35 transmitted or of obtaining higher amplification.

35 When an amplifier circuit arrangement according to the invention is used for television purposes it is not only desirable that the frequency characteristic curve should be flat, but also that the phase displacement φ brought about 40 by the amplifier should be proportional to the frequency of the oscillations to be amplified since otherwise distortion of the picture occurs. Thus, in the amplifier circuit arrangement the condition should be observed that the ratio φ/ω should 45 be constant throughout the range of frequencies. It is possible also to satisfy this requirement for a large range of frequencies by means of the

circuit arrangements according to the invention.

What is claimed is:

1. A circuit arrangement for amplifying electric oscillations comprising a plurality of vacuum tubes, at least one of said tubes having an anode circuit including an inductance and an ohmic resistance connected in series, and a second inductance and a condenser connected in series across said ohmic resistance, the circuit elements in said anode circuit being so chosen that in the equation representing the ratio of the amplification at an arbitrary frequency $V\omega$ to the amplification at a second and lower frequency V_0

$$15 \quad \frac{V\omega}{V_0} = \sqrt{\frac{1 + a_1\omega^2 + b_1\omega^4 + c_1\omega^6}{1 + a_2\omega^2 + b_2\omega^4 + c_2\omega^6 + d_2\omega^8}}$$

wherein the coefficients a_1 , b_1 , c_1 are functions of 20 said circuit elements at the frequency $V\omega$ and the coefficients a_2 , b_2 , c_2 , d_2 are functions of the said circuit elements at the frequency V_0 , the coefficients of the terms of equal order in the numerator and denominator being substantially equal to each other and the coefficient d_2 being as small as possible whereby the response of said circuit is substantially flat over the band between 25 said two frequencies.

2. A circuit arrangement for amplifying electrical oscillations having input and output terminals and comprising a vacuum tube having at least an anode a cathode and a control grid, said control grid and cathode being connected to said input terminals, a series connection of an inductance and an ohmic resistance connected between said anode and a source of anode potential, said inductance being adjacent said anode, a second series connection of an inductance and a condenser connected in parallel with said ohmic resistance, a second condenser connected between said anode and one of said output terminals, and the other of said output terminals being connected to said cathode, the elements in said anode circuit being so dimensioned that the response of said amplifier is substantially uniform over a wide band of frequencies.
